UNITED STATES PATENT OFFICE

JOHN F. PARSONS, OF SOUTH SAN GABRIEL, CALIFORNIA, ASSIGNOR OF ONE-HALF TO
AMELIA B. GRAHAM, OF SOUTH SAN GABRIEL, CALIFORNIA

SINGLE-SLIDE DINING TABLES

Application filed January 3, 1929. Serial No. 330,078.

This invention relates to tables of the extensible type and designed chiefly for dining.

One of the main objects is the provision of a table embodying a single movable slide and coacting parts, whereby either end portion of the table may be removed and used as a console, thus providing a pair of matched tables which may be easily and quickly assembled when a dining table is required.

While the drawing illustrates a preferred embodiment of the invention, it is to be understood that in adapting the means to meet specific needs and requirements, the design may be varied and such other changes in the minor details of construction may be resorted to within the scope of the invention as claimed, without departing from the spirit thereof.

For a full understanding of the invention and the merits thereof, reference is to be had to the following description and the drawing hereto attached, in which:

25 Figure 1 is a bottom perspective view of a table embodying the invention showing it extended.

Figure 2 is a transverse sectional view on the line 2—2 of Figure 1, the dotted lines showing a section of one of the leaves folded and partly folded and the folded sections moved to a central position.

30 Figure 3 is a horizontal section of the table adjacent the top and looking upwardly, with the end portions of the table brought together and the leaves folded and supported upon the slides.

Figure 4 is a vertical sectional view on the line 4—4 of Figure 3, looking in the 35 direction indicated by the arrows.

Figure 5 is a fragmentary view of adjacent end portions of a fixed and a movable slide.

Figure 6 is a detail sectional view showing the hinge joints between the sections comprising a leaf.

Figure 7 is a view of the parts illustrated in Figure 6, showing the sections folded.

Figure 8 is an end view of the parts 40 shown in Figure 7.

Corresponding and like parts are referred to in the following description and designated in the several views of the drawing by like reference characters.

The table comprises similar or like parts 55 each including a top 1, an end leg 2 and side legs 3. A rail 4 depends from the table top 1 and connects the upper ends of the legs 2 and 3 thereof. A brace 5 of approximately V-form connects the leg 2 to the legs 3 of each part of the table.

60 A metal bar 6 extends between the side legs 3 and is connected thereto, end portions of the bar being bent upwardly thence inwardly and secured to the underside of the table top 1. A bar 7 is connected at one end to the leg 2 and at its opposite end to the bar 6 by means of a splice piece 8. The end of the bar 7 attached to the leg 2 is bent upwardly thence inwardly and attached to 65 the under side of the table top 1. The bars 6 and 7 brace the legs and serve as means for positively connecting the legs to the table top 1. A fixed slide 9 extends from the 70 leg 2 and terminates about in line with the inner edge of the table top 1 and is attached to the bars 6 and 7. The fixed slide 9 is substantially of I-form in cross section, as indicated most clearly in Figure 2 of the drawings.

75 A movable slide 10 coacts with the slide 9 and receives the upper portion thereof, as illustrated most clearly in Figure 2 of the drawings. A movable slide 10 coacts with the slide 9 and receives the upper portion thereof, as illustrated most clearly in Figure 2 of the drawings. A movable slide 10 coacts with the slide 9 and receives the upper portion thereof, as illustrated most clearly in Figure 2 of the drawings. A movable slide 10 coacts with the slide 9 and receives the upper portion thereof, as illustrated most clearly in Figure 2 of the drawings.

80 A movable slide 10 coacts with the slide 9 and receives the upper portion thereof, as illustrated most clearly in Figure 2 of the drawings. A movable slide 10 coacts with the slide 9 and receives the upper portion thereof, as illustrated most clearly in Figure 2 of the drawings. A movable slide 10 coacts with the slide 9 and receives the upper portion thereof, as illustrated most clearly in Figure 2 of the drawings. A movable slide 10 coacts with the slide 9 and receives the upper portion thereof, as illustrated most clearly in Figure 2 of the drawings.

85 A movable slide 10 coacts with the slide 9 and receives the upper portion thereof, as illustrated most clearly in Figure 2 of the drawings. A movable slide 10 coacts with the slide 9 and receives the upper portion thereof, as illustrated most clearly in Figure 2 of the drawings. A movable slide 10 coacts with the slide 9 and receives the upper portion thereof, as illustrated most clearly in Figure 2 of the drawings. A movable slide 10 coacts with the slide 9 and receives the upper portion thereof, as illustrated most clearly in Figure 2 of the drawings.

90 A movable slide 10 coacts with the slide 9 and receives the upper portion thereof, as illustrated most clearly in Figure 2 of the drawings. A movable slide 10 coacts with the slide 9 and receives the upper portion thereof, as illustrated most clearly in Figure 2 of the drawings. A movable slide 10 coacts with the slide 9 and receives the upper portion thereof, as illustrated most clearly in Figure 2 of the drawings.

95 A movable slide 10 coacts with the slide 9 and receives the upper portion thereof, as illustrated most clearly in Figure 2 of the drawings. A movable slide 10 coacts with the slide 9 and receives the upper portion thereof, as illustrated most clearly in Figure 2 of the drawings.

100 When the end portions of the table are drawn apart the space between the tops 1 is filled by one or more leaves and, to pre-

vent misplacement of the leaves and to assure their being at hand when needed, each is connected to the movable slide 10 by means of a link 14. The link 14 also serves to support the leaf when in operative position, as indicated most clearly in Figures 1 and 2 of the drawings. Each leaf consists of complementary sections 15 and 16 of uniform length and width. These sections are hingedly connected to admit of one folding upon the other, as indicated most clearly in Figures 3 and 4 of the drawings. The links 14 are mounted in bearings 17 secured to the sections 15 and said sections in addition to turning upon the links are slidable thereon to admit of the leaves when folded occupying a medial position to be stowed beneath the tops 1 and rest upon the slide 10, as indicated most clearly in Figures 3 and 4 of the drawings.

The links 14 are elongated and are mounted in bearings 18 set into the movable slide 10. When the leaves are folded they occupy a position as to be out of the way and yet conveniently at hand when needed. Misplacement of the leaves is prevented by reason of the link connection thereof with the table. When the table is extended and the leaves in place between the tops 1 they are supported by the links 14 and dowels, as usually provided between the leaves of extension tables. When the clamp screws 11 are tightened the end portions of the table are held in adjusted position. If it be required to reduce the length of the table one, or both, of the clamp screws 11 is loosened and after the leaves, one or both have been folded, the end portions of the table may be pushed together. By separating the parts of the table either one or both may be used as a console. This is effected by removing one or both of the clamp screws 11, and when the end portions are separated either or both may be used as a console table as will be readily comprehended.

The leaves 15 and 16 may be hingedly connected in any determinate way. The hinge shown comprises complementary members and connecting links. Each of the hinge members includes a base 19, and a boss 20 in which are formed slots 21 for reception of the connecting links 22. The links 22 are of L-shape and are pivotally connected at the elbow, as indicated at 23. Each of the links comprises a short arm and a long arm and the links are oppositely disposed. The links are provided in sets and are arranged to inter-leave. The short arms of the links are pivoted to the base portions 19, as indicated at 24, whereas the long arms are connected by means of pins 25 the ends of which project and enter grooves 26 formed in the side walls of the slot 21. When the sections 15 and 16 are extended the hinges are concealed since

they are disposed wholly within the sections, as indicated most clearly in Figure 6 of the drawings. When the sections 15 and 16 are folded the elbows of the links project, as indicated most clearly in Figure 7 of the drawings. It is to be understood that the table may be of any form and size and may be mounted upon legs in any determinate way.

Having thus described the invention, I claim:

1. In a table including a top, an end and side legs, a bar connecting the side legs and having opposite end portions bent upwardly thence inwardly and secured to the legs and the top of the table, a second bar secured at one end to the first mentioned bar and having its opposite end bent upwardly thence inwardly and attached to the end legs and the top of the table.

2. In a table including a top, an end and side legs, a bar connecting the side legs and having opposite end portions bent upwardly then inwardly and secured to the legs and the top of the table, a second bar secured at one end to the first mentioned bar and having its opposite end bent upwardly then inwardly and attached to the end legs and the top of the table, a slide spaced from the top of the table and connected to the said bars.

3. A table comprising similar parts adapted for independent or conjoint use, each of the parts including a top, an end and side legs, a bar connecting the side legs, a centrally disposed fixed slide spaced from the top and connected to the end leg and the bar joining the side legs, and longitudinally slotted, a removable slide forming connecting means between the parts comprising the table and loosely engaging the fixed slides and extending across the top and along opposite sides thereof, and clamp screws passing through the slots of the fixed slides and carried by the removable slide to clamp the fixed slides between the embracing portions of the removable slide.

4. An extension table comprising similar parts adapted for independent use, each of the parts including a top, an end and side legs, a connecting bar between the side legs, a centrally disposed fixed slide spaced from the top and forming connecting means between the end leg and said side leg connecting bar, a removable slide connecting the parts and engaging the fixed slides thereof when the table as a whole is assembled, a sectional leaf for each part of the table, and a link for each leaf pivotally connected to the removable slide and having both pivotal and sliding engagement with a section of a leaf.

In testimony whereof I affix my signature.
JOHN F. PARSONS. [L. S.]
